UNITED STATES PATENT OFFICE

2,066,930

ELEVATOR

William F. Eames, Edgewood, Pa., assignor to
Westinghouse Electric Elevator Company, Chi-
cago, Ill., a corporation of Illinois

Application November 29, 1933, Serial No. 700,257
Renewed May 2, 1936

34 Claims. (Cl. 187—29)

My invention relates to signal and control systems for elevators and more particularly to such signals and control systems as may be employed for operating a bank of elevator cars wherein only a single push button for each direction at each floor is required for stopping the first one of the cars to approach for the desired direction.

One object of my invention is to provide a signal and control system which will promote the answering of calls and the loading and unloading of passengers in the most prompt and efficient manner.

Another object of my invention is to provide a system in which the registration of a stop signal by a passenger will stop only one car of a bank of cars and that car will be the nearest car approaching in the direction in which the passenger desires to travel at the time the stop signal is operated.

20 A further object of my invention is to provide a system in which, when a prospective passenger presses a call button to make a car stop for him in the direction he desires to travel, he will immediately receive a responsive (car will stop) signal from the nearest car approaching from that direction, so that he may walk immediately to the hatchway door for that car and be ready to step aboard it when the door opens.

A still further object is to provide a system in which a registered stop call will be appropriated by the nearest car at the instant the stop signal button is pressed, and in which that car and only that car will respond to the registered stop call.

A still further object of my invention is to provide a system in which the nearest approaching car will give an immediate responsive signal in answer to a registered stop call but in which an over-taking car will extinguish the responsive signal of the overtaken car, light its own responsive signal or floor lantern and stop for the passenger so that the waiting passenger may be informed when his registered stop signal is transferred to an over-taking car and move to the door of that over-taking car ready to step aboard when it stops and the door opens.

It is also an object of my invention to provide a system which the car attendant or dispatcher may easily set to operate either as a system wherein the nearest car at the time a call is registered will give a responsive signal and stop or a system in which the nearest approaching car in the desired direction will immediately give a responsive signal but the car which first actually arrives will take over the responsive signal and make the stop.

In order to accomplish these and other objects I have provided an elevator system embodying a group of cars and a signal and control system therefor having the following characteristics and

5 Each car in the group may be started by means of an up direction or a down direction switch in the car and may be stopped by stop push buttons in the car or by stop push buttons at the floor landings. The stop push buttons at the floor landings are common to all the cars; that is there is one up direction push button at each floor, the operation of which will stop a car for the up direction and a down push button at each floor which will stop a car in the down direction.

10 Under one operation of my system, when a push button at a floor is pressed to register a stop call, the floor lantern at that floor for the nearest approaching car for a corresponding direction will light immediately regardless of how far the car is 15 from that floor, to indicate to the passenger that his stop call has been registered and which car will answer it. The floor lantern will remain lighted until the car reaches that floor.

Under the other operation of my system, when 20 a push button at a floor is pressed to register a stop call, the floor lantern at the floor for the nearest approaching car for the corresponding direction will light immediately regardless of how 25 far the car is from that floor, to indicate to the passenger that his call has been registered and which car will answer it, but if another car overtakes the first-mentioned car, the overtaking car will transfer the registered call to itself; that is, 30 it will extinguish the floor lantern of the first-named car, then light its own floor lantern and proceed to stop at the floor in response to the registered call when it arrives at the floor.

Readily available switches are provided for 35 conditioning the system for operation in either manner.

The above mentioned objects and other objects which will be made apparent throughout the further description of my invention may be attained 40 by means of the system hereinafter described and illustrated in the accompanying drawings, in which:

Figure 1 is a diagrammatic representation of 45 an elevator installation embodying my improved signal and control system;

Fig. 2 is an enlarged representation of the contact segments and cooperating contact brushes on one of the floor selectors for one of the cars shown in Fig. 1, with the car stopped at the first floor.

50 Figs. 3, 4 and 5 collectively, constitute a diagrammatic representation, in what is known as the straight line style, of the signal and control system employed in operating the elevator cars shown in Fig. 1; and

Figs. 3A, 4A and 5A collectively, constitute an explanatory illustration of the relays embodied in Figs. 3, 4 and 5.

55 The illustration of the relays in Figs. 3A, 4A and 5A shows their coils and contact members

disposed on horizontal lines corresponding to their positions in the straight line circuits of Figs. 3, 4 and 5, so that the reader may readily determine the identification of any relay, the number and kind of its contact members and the position of its coil and its contact members in the straight line circuits.

For convenience in reading the drawings, Fig. 4 should be placed under Fig. 3, Fig. 5 under Fig. 10 4, Fig. 3A beside Fig. 3; Fig. 4A beside Fig. 4 and under Fig. 3A; and Fig. 5A beside Fig. 5 and under Fig. 4A.

Referring more particularly to the drawings, I have illustrated an elevator system embodying 15 two cars A and B for serving five floors or landings. The cars are suitably suspended by cables 11 and 12 which pass over drums 13 and B13, respectively.

Although I have shown only two cars and a 20 signal and control system therefor, as applied to only five floors, it should be understood that the invention is equally applicable to any desired number of cars operating past any desired number of floors.

25 For convenience, the main relays included in the system are designated as follows:

- C=Stop push buttons in car A.
- CC=Holding coils for car buttons.
- 30 CK=Relay for cancelling floor button calls by car A.
- CS=Relay responsive to car buttons for stopping car A.
- D=Down direction switch for car A.
- 35 DG=Down zone relays. Common to both cars.
- DH=Down false call preventing relays. Common to both cars.
- DR=Relays for registering stop calls on down floor buttons. Common to both cars.
- 40 DRS=Coils for cancelling down stop calls on floor buttons. Common to both cars.
- E=Inductor relay for decelerating car A.
- EG=Relay for inductor locking relay circuit.
- EM=Inductor restoring relay for car A.
- 45 F=Stop push buttons at floors. Common to both cars.
- FS=Relay responsive to the floor buttons for stopping car A.
- J
- 50 K Storing relays which operate in conjunction with the floor relays for transferring L and storing floor stop calls until the calls N are answered and for lighting the immediate signal lamps. Common to both O cars.
- 55 P
- Q
- PS=Bypass relay.
- S=Inductor relay for stopping car A.
- T=System selecting relay.
- 60 U=Up direction switch for car A.
- UG=Up zone relays. Common to both cars.
- UH=Up false circuit preventing relays. Common to both cars.
- UR=Relays for registering stop calls on up floor buttons.
- 65 URS=Coils for cancelling up stop calls on floor buttons.
- V=High speed relay for car A.
- W=Up direction preference relay for car A.
- 70 X=Down direction preference relay for car A.
- Y=Auxiliary up direction preference relay for car A.
- Z=Auxiliary down direction preference relay for car A.
- 75 The relays for car B are given the same design-

nation as those for car A with the letter B prefixed thereto. The letters U and D indicate up and down direction. The prefix numerals indicate the floors. The suffix numerals indicate the contact members of the relays.

5 Referring to the control system for car A as shown in Figs. 3 and 4, the hoisting drum 13 is directly coupled to an armature 17 of a hoisting motor 18, the field winding 19 of which is connected, for constant voltage energization, to a 10 source of supply designated as the supply conductors L+ and L-.

A variable voltage system of control may be provided for operating the hoisting motor 18 wherein the armature 17 is connected in a closed 15 circuit with the armature 21 of a generator 22. The generator is provided with a separately excited field winding 23 and a cumulative series field winding 24. A resistor 24R is connected in the circuit of the separately excited field winding 23 for controlling the speed of the generator. The armature 21 of the generator may be driven by a suitable driving motor 25 which may be connected to a suitable source of supply, as represented by the conductors and switch 26.

25 A brake 5 operated by a brake magnet 6 is provided for applying a braking effect to the hoisting drum 13 when the car is brought to a stop, the brake magnet 6 being energized to release the brake 5 when the car is running and being deenergized to apply the brake 5 when the supply of power to the car is cut off.

The direction and speed of the hoisting motor 18 may be suitably controlled by controlling the 35 direction and the value of the excitation current that is supplied to the separately excited field winding 23 of the generator 22.

The direction of excitation current for the field winding 23 may be suitably controlled by means of an up direction switch U and a down 40 direction switch D, while the value of the current supplied to the field winding may be controlled by means of a high speed relay V which controls the resistor 24R.

The operation of the up direction and the down direction switches U and D, as well as the high speed relay V, may be controlled by means of an up push button UP and a down push button DP that are mounted in the car in position to be actuated by the car attendant.

50 Any suitable means may be employed for automatically stopping the car A level with the floors it serves. As an example of such means, I have illustrated an automatic inductor landing system similar to that disclosed in the patent of E. M. Bouton, No. 2,001,563, and assigned to the Westinghouse Electric & Manufacturing Company.

55 The inductor landing system for car A includes a decelerating inductor relay E and a stopping inductor relay S for causing the car to be automatically decelerated from its high speed and brought to a stop at an exact level with the floor. The decelerating inductor relay E is mounted on the car A in position to cooperate with an inductor plate UE for the up direction and an inductor plate DE for the down direction. The stopping inductor relay S is mounted on the car A in position to cooperate with an inductor plate US for the up direction and an inductor plate DS for the down direction. The inductor plates are constructed of magnetic material and are mounted in the hatchway in such position as to cooperate with and open the contact members of the inductor relays on the car when the 70 75

relays are in an energized condition as the car approaches a stop at a landing.

For simplicity, only one set of inductor plates for one floor has been shown, but it will be understood that a set similar to that shown may be provided for each floor served by the car intermediate the upper terminal landing and the lower terminal landing. If desired, a set of inductor plates corresponding to the inductor plates US and UE may be provided for the upper terminal floor and a set corresponding to inductor plates DE and DS may be provided for the lower terminal floor.

As shown, each inductor relay is provided with two sets of contact members. For an "up" stop, the contact members E₁ of the relay E cooperate with the inductor plate UE in decelerating the car, and the contact members S₁ cooperate with the inductor plate US in stopping the car after it is decelerated. For the down direction, the contact members E₂ of relay E cooperate with the inductor plate DE to decelerate the car A and the contact members S₂ cooperate with the inductor plate DS in stopping the car.

The contact members just described are so connected with the car control circuits that, when the inductor relays are energized to decelerate and stop the car at the floor represented by the inductor plates in the down direction, the contact members E₂ pass the inductor plate DE and are thereby opened to decelerate the car, and as the contact members S₂ come opposite the inductor plate DS they open to stop the car level with the floor. The contact members E₁ of relay E and the contact members S₁ of the relay S are opened by the inductor plates UE and US respectively when the stop is to be made in the up direction.

When the inductor relays are energized to slow down the car to a stop, it is desired to maintain them in that condition until they are operated to bring the car to rest. A slow down holding relay EG is provided for this purpose.

When the inductor relays are energized for a stop, they remain energized until restored even though their contact members are operated by passage near the inductor plates. Therefore, an inductor restoring relay EM is provided for deenergizing the inductor relays of car A after a stop has been made and also for interlocking them so that they can be energized only when the car is moving.

In the elevator system illustrated in the drawings the energization of the inductor relays on car A for decelerating and stopping that car at a floor is effected either by a car button stopping relay CS or by a floor bottom stopping relay FS. The energization of either of these relays will, as the car nears a floor at which a stop is to be made, energize the inductor relays on that car and thereby cause it to decelerate and stop at that floor.

The car button stopping relay CS is controlled by push buttons in the car A; that is, the pressing of a car button by a car attendant will register a stop call, or in other words, initiate and maintain a circuit which will be completed as the car nears the floor corresponding to the button to thereby energize the stopping relay CS which will, in turn, energize the inductor relays to stop the car at that floor. In this manner, the car may be stopped at a floor by pressing a push button in the car for that floor.

The push buttons mounted in the car A for operation by the car attendant when he desires

register stop calls to stop the car at the floors where passengers desire to get off, are designated as 2C, 3C and 4C for the second, third and fourth floors, respectively, no buttons being necessary for the lower terminal floor and the upper terminal floor because the car may be stopped by the usual well-known limit switches (not shown) as it approaches these terminals.

Associated with the respective car push buttons are car push-button holding or registering coils 10 2CC, 3CC and 4CC. These coils operate to hold the car push buttons in a depressed position after they are pressed by the car attendant in making stops from within the cars. The coils are deenergized when the car reaches the terminals to release the buttons for the next direction of operation.

The floor button stopping relay FS is controlled by push button switches at the floor landings; that is, the pressing of a floor button will register, 20 or in other words, initiate and maintain a circuit which will be completed as the car nears that floor and thereby energize the stopping relay FS, which will, in turn, energize the inductor relays to stop the car at such floor. It should be noted here 25 that while the car buttons are individual to each car, the floor buttons are common to both cars; that is, there is only one button for each direction at each floor regardless of the number of cars and the waiting passenger needs to press only one 30 button to stop a car for him in the direction in which he desires to go.

The push buttons disposed at the floor landings (see Fig. 5) are designated as follows: The "up" buttons are marked, 1UF at the first floor, 2UF 35 at the second floor, 3UF at the third floor and 4UF at the fourth floor. The "down" floor buttons are marked 5DF at the upper terminal, 4DF at the fourth floor, 3DF at the third floor and 2DF at the second floor. Inasmuch as the cars do not 40 go below the first floor, no "down" button is provided for the first floor. Similarly, as no car goes above the fifth floor, no "up" button is provided for the fifth floor.

Associated with the floor push buttons are stop 45 call registering relays 1UR, 2UR, 3UR and 4UR for the "up" direction and 5DR, 4DR, 3DR and 2DR for the "down" direction. These relays operate to maintain a floor button circuit in a partially completed condition after its button is 50 pressed until the car answers the registered call by stopping at the floor.

A cancellation coil is also mounted upon the body of each of the registering relays for the purpose of deenergizing that relay when the call 55 is answered, the coils being designated as 1URS, 2URS, 3URS, 4URS for the "up" direction and 5DRS, 4DRS, 3DRS and 2DRS for the down direction.

In order that a waiting passenger at a floor 60 landing may be immediately informed or signalled upon pressing a floor push button, that his stop call has been registered and also which car approaching in the direction he desires to go will stop for him at his landing, I have provided a plurality 65 of signal or indicating devices, preferably electric lamps, which are mounted outside of the elevator shafts at the floor landings and are usually known as floor lanterns.

Each of the top and bottom floors is provided 70 with a single signal device or floor lantern for each car; but each of the intermediate floors is provided with a pair of lanterns for each car, one lantern to indicate that the corresponding car is approaching for the "down" direction and will 75

make a "down" stop at the floor, and the other lantern for indicating that the car is approaching for an "up" direction and will make an "up" stop. This responsive signal is given immediately upon 5 the pressing of the floor button even though the car may be many floors away and even though it may not have yet "rounded" the terminal between it and the registered call.

The floor lanterns for car A (see Fig. 3) are 10 designated as 1UL, 2UL, 3UL and 4UL for the "up" direction at the first, second, third and fourth floors, and 5DL, 4DL, 3DL and 2DL for the fifth, fourth, third and second floors in the "down" direction.

15 The floor lanterns for car B (see Fig. 5) are given the same designations with the letter "B" prefixed thereto.

In order to provide for the immediate illumination of the floor lanterns in response to the registration of a call so that the passenger may step 20 to the door indicated and be ready to board the car when it arrives, I have provided a plurality of zoning relays (see Fig. 4) designated as 1UG, 2UG, 3UG and 4UG for the "up" direction, and 25 5DG, 4DG, 3DG and 2DG for the "down" direction.

These zone relays are common to both cars and divide the complete round trip shaft travel of all 30 cars into as many signal zones as there are cars operated. They assign one zone to each car. The zone that is assigned to any one car is the zone in advance of that car's motion up to the next car in front of it. The zone for each car is elastic and keeps moving along with the car, its length 35 being determined by the position of the car itself, and by the position of the next car ahead.

A plurality of storing relays for each car are provided for operation in conjunction with the floor relays and the zoning system for storing the 40 registered stop calls in connection with the nearest car in the desired direction until the calls are answered and for lighting the immediate signal lanterns. The storing relays for car A for the "down" direction are designated as J, K, L and M 45 and those for the "up" direction as N, O, P and Q. The storing relays for car B are given the same letters with the letter "B" prefixed thereto.

A cancellation relay CK is provided for operating in conjunction with relay EM in cancelling the 50 stop calls registered on the floor buttons.

In order that certain circuits may be conditioned for operation in the "up" direction when car A is moving upwardly and other circuits be conditioned for operation only when car A is moving 55 downwardly, I have provided an "up" direction preference relay W, a "down" direction preference relay X, an auxiliary "up" direction preference relay Y and an auxiliary "down" direction preference relay Z for car A.

60 A plurality of preventing relays are provided for preventing a registered call from affecting more than one car at one time. The preventing relays (see Fig. 4) are common to both cars and are designated as 1UH, 2UH, 3UH and 4UH 65 for the "up" direction and 5DH, 4DH, 3DH and 2DH for the "down" direction.

At various times in the operation of the elevator system a car may be so loaded that the operator may desire to run past the outside stop 70 calls for various floors. To permit this operation, a by-pass or transfer push button 45 (see Fig. 1) is mounted in car A and a similar by-pass or transfer button 46 is mounted in car B. As long as the car attendant presses the by-pass 75 button in his car that car will not answer or stop

at any floor button call or light its floor lantern. As soon as the button is released the car will again respond to outside calls, light its floor lanterns, etc.

A by-pass or transfer relay PS is provided for 5 energization by the pressing of by-pass button 45 in car A to so modify the control circuits as to effect the various functions described in the by-pass operation of car A. Similarly a by-pass relay BPS is provided for energization by the press- 10 ing of the by-pass button 46 in car B.

The present system is so constructed that it is possible to operate by two methods of control.

In order that the system may be operated in either manner, I have provided a system selecting relay T for car A and a similar relay BT for car B. The relays T and BT are controlled by 15 push button switches 47 and B47, which may be located at any place where they may be easily operated by the dispatcher. 20

If desired the conductors to the switches 47 and B47 may be so connected as indicated by the arrows 70 and 71 that one switch will control both relay T and BT.

In the one method of operation, when the 25 switches 47 and B47 are opened to deenergize the system relays T and BT, the system will so operate that the nearest car in the desired direction will, when a call is registered, immediately give a 30 responsive signal and appropriate the call to itself and stop in answer to the call. In other words, the first car to get the call will make the stop regardless of which car arrives first.

In the other method of operation when the 35 switches 47 and B47 are closed to energize the system relays T and BT, the system will so operate that, although the nearest approaching car in the desired direction to a registered floor stop call will immediately give an answering signal by lighting 40 its floor lantern, if another car overtakes that car, the overtaking car will take over the registered signal, light its own floor lantern and stop itself at the floor in response to the stop call. In other words, the first car to arrive will answer the call 45 regardless of which car first picked up the call.

In order that the various circuits for the push buttons, floor lanterns, relays, etc., may be connected in accordance with the position of the cars with respect to the floors past which they operate, the car A is provided with a floor selector 50 SE and the car B with a floor selector BSE. The floor selectors may be of any suitable type such as are usually employed in elevator systems and may be located at any suitable point such, for example, as in the penthouse or in the elevator 55 shafts.

The floor selector SE for car A, is provided with a set of up contact segments and a set of down contact segments as shown in Fig. 2 which are arranged according to the floors and are disposed 60 to be engaged by cooperating brushes 30 to 43 inclusive, mounted upon and insulated from a movable arm SM.

The movable arm SM is operated in accordance with the movements of the car A by means of a 65 screw shaft 44 that may be driven by some part of the operating mechanism of that car. The frictional engagement between the arm SM and its operating screw shaft 44 will cause the arm to bear upon the "up" contact segments when 70 the car is traveling upwardly and, upon the "down" contact segments when the car is traveling downwardly, it being understood that the arm will tilt from one position to the other when the direction of operation of the car is reversed. 75

For a more complete detailed description of the type of floor selector employed, reference may be had to the Smalley and Reiners patent 634,220 of October 3, 1899.

5 The group of up contact segments designated as *a* under the brush 30 completes the circuits for cancelling the up floor button calls.

The group of "up" contact segments designated as *b* under the up brush 31 are energized when 10 stop calls are registered on the floor buttons for the purpose of energizing the floor button stopping relay to stop the car on its up trip when it approaches a floor at which an up stop is to be made.

15 The group of up contact segments designated as *c* under the up brush 32 are energized by the pressing of the car buttons so that the approach of the car to a floor for which a car button has been pressed will cause the energization of the 20 car button stopping relay and thereby effect the stopping of the car at that floor.

A group of up contact segments designated as *d* under the up brushes 33 and 34 may be called the "nearest car segments" as they connect the 25 circuits for energizing the storing relay for the car nearest to a registered floor call. The storing relays in turn, light the floor lantern of the nearest car to give an immediate responsive signal for that car and also energize the contact segments 30 *b* under brush 31 to effect the stopping of that car when it arrives at the floor.

The up brush 33 is an advance brush and the up brush 34 a standing brush in order that the 35 storing relays may be kept energized not only while the car picks up the call but also while the car comes into and stands at a floor.

The up contact segments designated as *e* under the up brushes 35 and 36 serve to connect the 40 circuits for controlling the zone relays while the car is traveling upwardly. The up brush 35 is an advance brush and the brush 36 is a standing brush to correctly position the zone circuits while the car is running and also while it is standing at a floor.

45 The contact segments on the down side of the floor selector are engaged by the down brushes 37 to 43 when the car is descending and correspond to the contact segments just described for the up direction, those marked *f* being the floor 50 button cancelling segments; *g* the down floor button stopping segments; *h* the down car button stopping segments; *i* the nearest down car selecting and lantern lighting segments, and *j* the down zoning segments.

55 The floor selector BSE is similar to the one described for car A.

Inasmuch as the control system for car B is similar to that just described for car A, a detailed 60 description of the control system for car B will not be given.

The invention may be understood best by an assumed operation of the system illustrated in the drawings.

65 *Assumed operation of the system with the relays T and BT deenergized*

It will be assumed that car A is standing at the third floor with its door open; that car B is standing at the 2nd floor; and that the system 70 selecting switches 47 and B47 are open, to deenergize the system selecting relays T and BT, whereby the nearest car for a stop call will appropriate the call to itself and stop in answer thereto.

75 The switch 26, Fig. 3, and the switch B26,

Fig. 5, are closed to start the motor-generator sets of cars A and B. The switch 27 (Fig. 3) is closed to prepare the control systems of both cars for operation. Inasmuch as the control systems for both cars are the same, only that for car A will be described at present.

The closing of the switch 27 energizes the supply conductors L+ and L-, thereby energizing the field winding 19 of the hoisting motor 18 of car A to prepare it for operation. The closing 10 of the switch 27 also energizes the down direction preference relay X for car A which opens its contact members X2 to lock out the up direction preference relay W.

15 It may be noted that, when the car is first 15 thrown into service, the direction preference relays for either direction may become energized but that as soon as the up direction or the down direction switch is operated, the correct direction preference relay for that direction will also be 20 energized by reason of the opening of the contact members D7 or U7 in the circuits of the direction preference relays.

The circuit of the energized direction relay X 25 extends from the supply conductor L+ through the coil of relay X, contact members U7 and W2 to the supply conductor L-.

The energization of the down direction relay X closes its contact member X4, thereby completing a circuit from the supply conductor L+ 30 to the supply conductor L- for energizing the car button holding coils 4CC, 3CC and 2CC, so that if one of the car buttons is pressed by the car attendant, it will be held in its pressed condition until the car reaches the lower terminal, 35 whereupon the buttons will be released when the holding coils CC are deenergized by the deenergization of the down direction preference relay X.

The energization of the direction relay X 40 closes its contact members X3, thereby energizing the auxiliary down direction preference relay Z for car A by way of a circuit extending from the supply conductor L+ through the coil of relay Z and the contact members X3 and PS! 45 to supply conductor L-.

The energization of the auxiliary down direction preference relay Z closes its contact members Z3 (Fig. 4) thereby energizing the down zone relay 3DG at the third floor by a circuit extending 50 from supply conductor L+4 through the coil of relay 3DG, the floor selector contact segment 3j, the selector brush 43, and the contact members V8 and Z3 to the supply conductor L-4.

The energization of the down zone relay 3DG 55 opens its contact members 3DG1 in a normally closed zone circuit 49 for car A.

In considering the zone relay 3DG, it should be noted that the zone ring circuit 49 of car A (Fig. 3) is divided into a plurality of sections by 60 the zone relay contact members 3DG1, etc. The car B is provided with a similar zone ring circuit B49 (Fig. 5) which is divided into a plurality of sections by contact members 3DG2, etc. The zone relays are controlled by the positions of 65 the cars through the engagement of brushes on the contact segments of the floor selectors, as represented in the right-hand portion of Fig. 4. Thus, when a car is at a floor, the zone relay G for that floor is energized by that car causing its 70 own brush to engage its own zone contact segment for that floor.

The zone relays are common to both cars, and each relay is provided with two pairs of contact members, one pair being in the ring circuit for 75

car A, and the other pair being in the ring circuit for car B; thus when any zone relay is energized it opens one pair of contact members in its zone circuit.

5 Inasmuch as the zone relays are common to both cars and are controlled by the positions of the cars, they operate to divide the ring circuits into zones, one zone for each car. The zone for any car, as previously described, extends from 10 that car up to the next car ahead.

For instance, with car B standing at the second floor on an up trip, as shown, its brush B43 is on the contact segment B2j; thereby energizing the relay 2DG to open its contact members 15 2DG1 in the ring circuit 49 of car A and its contact members 2DG2 in the ring circuit B49 of car B. With car A at the third floor and with the zone relay 3DG energized as described to open its contact members 3DG1 in ring circuit 49 and 20 its contact members 3DG2 in the ring circuit B49, the ring circuits are divided into zones for each car. The zone for car A now defined by the ring circuit 49 extends downwardly from the third floor to the lower terminal and up to car B 25 at the second floor; while the zone for car B now defined by the ring circuit B49 extends from car B at the second floor up to the upper terminal and down to car A at the third floor.

By means of the zone system, if a floor push 30 button is operated in the zone for car A, only car A will be affected thereby, and if a floor push button is operated in the zone for car B, only car B will be affected thereby. It is also to be 35 noted that the zones are elastic; that is, they travel in front of the car and keep moving with the car.

It may also be noted here that the high-speed 40 relay for each car controls the advance and the standing zone brushes for that car. For instance, the high-speed relay V of car A closes its contact members V8 leading to brush 43 when that car is standing at a floor on a down trip, but opens its contact members V8 and closes its contact members V9 leading to brush 42 when the 45 car starts to move. The advance position and standing position are provided because a car just moving past a floor should not include that floor in its zone, but a car standing at a floor should include that floor in its zone.

50 It will now be assumed that a waiting passenger at the second floor, desirous of making a "down" trip, presses the "down" button 2DF at the second floor. The operation of this push button will cause the nearest approaching car 55 in the desired direction (now car A) to give an immediate reply signal indicating the door at which it will stop and will also cause the car to stop when it arrives at that floor on its "down" trip.

60 By the term "nearest approaching car", I mean that car whose position, direction of operation and distance from said floor will permit the car-stopping system (inductor relays, etc.) to stop it at that floor when it arrives thereat. In other 65 words, it means the car which is still capable of being stopped at the floor at which the stop call is registered at the time the call is registered.

The pressing of the button 2DF closes the circuit for energizing the call-registering relay 2DR 70 by a circuit extending from supply conductor L+3 through the contact members of button 2DF, the coil 2DR and conductors 57 and 58 to the supply conductor L-3 (Fig. 4).

75 The energization of the registering relay 2DR closes its contact members 2DR2 to provide a

self-holding circuit for itself whereby the call may be said to be registered; that is, a single pressing of the button 2DR is sufficient to energize the registering coil 2DR and cause it to remain energized until the stop call is answered by the stopping of the car.

The closing of the contact members 2DR3 of the relay 2DR closes a gap in the circuit of the storing relay BM for car B but that relay fails to become energized because car B with which it is associated is standing at the second floor on an up trip with its brush B36 disposed on the contact segment B2e whereby the zone relay 2UG is energized to open its contact members 2UG2 in the zone ring circuit B49, and with car 15 A standing at the third floor on its down trip, the zone relay 3DG is energized to open its contact members 3DG2 in the zone circuit B49, thus preventing any current flowing through the coil of storing relay BM and the "live" brush B34 of 20 car B. Therefore it is seen that the zoning system prevents the car farthest away in point of travel from the registered call at the second floor, from receiving that registered call.

The energization of the registering relay 2DR closes its contact members 2DR1, thereby energizing the storing relay M for car A by a circuit extending from the supply conductor L+ through the contact members 2DR1, the coil M, the contact members 2DH1, part of ring circuit 49, contact members 2DG1, contact segment 3i, brush 41, and the contact members V3 and Z2 to the supply conductor L+.

The energizing of the storing relay M closes 35 its contact members M2 to provide a self-holding circuit which extends from the coil M through the contact members M2 and T11, the conductor 60 and the contact members PS2 to the supply conductor L-.

The energization of the storing relay M also 40 closes its contact members M1 for immediately lighting the down floor signal lantern 2DL at the second floor to indicate to the intending passenger that his stop call has been registered and that car A will stop at the second floor on its down trip, so that he may at once walk to the door for that car and be ready to board it when it stops and the door opens. The circuit for this signal extends from the supply conductor L+2 45 through the contact members M1 and the down floor lantern 2DL to the supply conductor L-2. Inasmuch as the down signal lantern 2DL is lighted in immediate response to the operation of the floor button 2DF, the waiting passenger may at 55 once walk to the door for car A and be ready to board that car when it stops at the second floor and opens its door.

The energization of the relay M also closes its contact members M3, thereby completing a circuit for energizing the preventing relay 2DH by way of a circuit extending from the supply conductor L+4 through the contact members M3 and the coil 2DH to the supply conductor L-4. The energization of the relay 2DH opens its contact members 2DH1 in the signal circuit for car A and its contact members 2DH2 in the signal circuit for car B. The opening of the contact members 2DH1 does not affect the signal circuit for car A because relay has closed its self-holding circuit. The opening of 2DH2 prevents car B from picking up the call even if it should pass car A and arrive at the second floor ahead of car A.

The energization of the storing relay M in clos- 75

ing its contact members **M1** also energized or rendered alive the down contact segment **2g**.

Inasmuch as car A is now standing at the third floor which is only one floor away from the floor at which the next stop is to be made, its down brush **38** is disposed on the live segment **2g** and the car button stopping relay **FS** is thereby energized to effect the stopping of the car at the second floor after it leaves the third floor on resuming its down trip. The circuit for the relay **FS** extends from the supply conductor **L+2** through contact members **M1**, contact segment **2g**, brush **38**, the contact members **Z1** of the auxiliary direction relay **Z** and the coil **FS** to the supply conductor **L-2**.

It will be assumed that the car attendant closes the elevator door thereby closing the door and gate contact members **61** and starts the car downwardly by pressing the down push button **DP**. The pressing of the button **DP** completes a circuit for energizing the inductor storing relay **CK** and the down direction switch **D**, which circuit extends from the supply conductor **L+1** through the contact members of push button **DP**, the contact members **S2** of the stopping inductor relay **S**, the contact members **U5**, the coil of down direction switch **D**, the coil of inductor restoring relay **CK** and the door and gate contact members **61** to the supply conductor **L-**. The energization of the relay **CK** closes its contact members **CK1** to prepare for cancelling the stop call at the second floor.

The energization of the down direction switch **D** closes its contact members **D5**, thereby completing a self-holding circuit for itself and the relay **CK**, extending from the supply conductor **L+1** through conductor **62**, the contact members **D5, S2**, and **U5** to the coil **D**.

The energization of down direction relay **D** also closes its contact members **D1** and **D2** to energize the separately excited field winding **23** of the generator **22**, by a circuit extending from the supply conductor **L+1** through the contact members **D2**, the separately excited field winding **23**, the contact members **D1** and resistor **24R** to the supply conductor **L-**. The energization of the down direction switch **D** also closes its contact members **D3**, thereby energizing the brake magnet **6** and the inductor restoring relay **EM** for operating in conjunction with the sequence relay **CK** for cancelling calls.

Inasmuch as the field winding **23** is energized and the brake **5** is released by the energization of the brake magnet **6**, the generator **22** supplies current to the hoisting motor **18** which, in turn, operates the hoisting drum **13** to lower the car in the hatchway (not shown).

The energization of the down direction switch **D** also closes its contact members **D6**, thereby energizing the high speed relay **V** by a circuit extending from the supply conductor **L+1** through contact members **D6** and **E2** and a coil **V** to the supply conductor **L-**.

The energization of the high speed relay **V** closes its contact members **V1** to eliminate the resistor **24R** from the circuit of the field winding **23** of the generator **22**, thereby causing the variable voltage system to operate the car at high speed.

The energization of the relay **EM** closes its contact members **EM1**, thereby preparing the circuits of the decelerating and stopping inductor relays for energization.

The energization of the car button stopping relay **FS** heretofore referred to in stopping the

car closes its contact members **FS1**, thereby energizing the decelerating inductor relay **E** by a circuit extending from supply conductor **L+1** through contact members **FS1**, the coil **E** and contact members **EM1** to the supply conductor **L-**. The 5 inductor relay is now ready to cause the deceleration of the car when it passes the high speed inductor plate as the car approaches the second floor.

The closing of the contact members **FS1** also 10 energizes the inductor holding or locking relay **EG** which closes its contact members **EG1** to constitute a holding circuit for the decelerating inductor relay **E**.

The car now moves downwardly and in so doing 15 causes the down brush **38** to leave the contact segment corresponding to the second floor, thereby deenergizing the car button stopping relay **FS**, however, the decelerating inductor relay is now energized and will function at the proper time to 20 decelerate the car for this second floor stop.

As the car A continues toward the second floor, its decelerating inductor relay **E** passes the down high speed plate **DE** for the second floor and is thereby operated to open its contact members **E2**, 25 thereby deenergizing the high speed relay **V** which opens its contact members **V1** and thereby reinserts the resistor **24R** in the circuit of the generator field winding **23** for decelerating the car from high speed to its stopping speed. 30

The deenergization of the high speed relay **V** also closes its contact members **V2** thereby energizing the stopping inductor relay **S**. The stopping inductor relay **S** is now energized and will be operated to bring the car to a stop at the sec- 35 ond floor as soon as it comes opposite the inductor plate **DS**.

As car A approaches closely to the second floor at its stopping speed, the inductor relay **S** comes opposite the inductor plate **DS** and is thereby 40 operated to open its contact members **S2**, thus deenergizing the inductor restoring relay **CK** and the down direction switch **D**.

The deenergization of the down direction switch **D** opens its contact members **D1** and **D2** to 45 deenergize the generator field **23**; opens its contact members **D3** to deenergize the brake magnet **6** and apply the brake **5** and to deenergize the inductor restoring relay **EM**. The deenergization of the field winding **23** and the application of 50 the brake **5** causes the car to stop level with the second floor; and the deenergization of the relay **EM** opens its contact members **EM1** to deenergize and restore the inductor locking relay **EG**, the decelerating inductor relay **E** and the stopping inductor relay **S**, so that they will not be effective to stop the car in its future operation until the car button stopping relay **CS** or the floor button stopping relay **FS** is again energized to effect the stopping of the car. 60

The elevator door and gate may now be opened thereby opening the door and gate contact members **61** to prevent operation of the car while it is taking on or discharging passengers.

Assume now that the car attendant desires to 65 move the car down to the first floor and therefore closes the door and gate and presses the "down" push button **DP** in the car. The pressing of the down button **DP** energizes the down direction switch **D** and the cancellation relay **CK**. 70 The energization of the down direction switch **D** causes the car to start downward as previously described.

The energization of the cancellation relay **CK** closes its contact members **CK1**, thereby com- 75

pleting a circuit for energizing the call restoring coil **2DRS** for the second floor by a circuit extending from the supply conductor **L+3** through the contact members **2DR2**, the relay **2DRS**, contact segment **2f**, brush **37**, and thence through the contact members **X5**, **V1**, **EM2** and **CK1** to the supply conductor **L-3**.

It will be noted here that the lower end of the stem of inductor restoring relay **EM** (see Fig. 10 **4A**) bearing the contact members **EM2** is provided with a dashpot **63** and is connected by a spring **64** to the main stem so that the contact members **EM2** will not close for a predetermined period of time after the relay **EM** is energized. 15 **15** This delay in the closing of the contact members **EM2** permits those contact members to cooperate with the contact members **CK1** of the cancellation relay **CK** in energizing the restoring relay **2DRS** when the car is ready to leave 20 the second floor.

The energization of the restoring relay **2DRS** deenergizes the call registering relay **2DR** thereby cancelling the call at the second floor and causing the relay to open its self-holding contact members **2DR2** and also to open its contact members **2DR1** for deenergizing the storing relay **M**, which, in turn, opens its contact members **M1** thereby extinguishing the down floor lantern **2DL** for car **A** at the second floor and also opens 25 its contact members **M3** to deenergize and restore the preventing relay **2DH**.

It will be assumed that car **A** has now run into and is stopped at the lower terminal by the usual and well known limit switches (not shown).

35 Referring now to car **B** which is shown in the drawings as standing at the second floor on an up trip, under these conditions, its up direction preference relay **BW** is energized by a circuit extending from the supply conductor **L+5** (Fig. 5) 40 through the coil **BW** and the contact members **BD1** and **BX2** to the supply conductor **L-5**. The closing of the contact members **BW1** of relay **BW** (Fig. 4) prepares a circuit leading through the up brush **B30** for energizing the floor call 45 restoring relays. The opening of the contact members **BW2** of relay **BW** (Fig. 5) interlocks the down direction relay **BX** to prevent its energization. The closing of the contact members **BW3** closes the circuit leading to brush **B32** so 50 that the car button stopping relay **BCS** may be energized by the operation of a car button.

By closing of the contact members **BW5** of relay **BW** completes a circuit for energizing the holding coils **2BCC**, **3BCC** and **4BCC** in car **B**, 55 for holding the car push buttons **2BC**, **3BC** and **4BC** in a closed position after they are operated for the purpose of registering a stop call at a floor from within the car **B**.

The closing of the contact members **BW4** completes a circuit for energizing the auxiliary up direction preference relay **BY**, which circuit extends from the supply conductor **L+5** through the coil **BY**, the contact members **BW4** and **BPS4** to the supply conductor **L-5**.

65 Assuming now that the attendant in car **B** closes its door and gate, thereby closing the door and gate contact members **B61** and also presses the up button **BUP** to move the car upwardly.

The pressing of the button **BUP** completes a 70 circuit for energizing the floor button cancellation relay **BCK** and the up direction switch **BU**. The energization of the relay **BCK** prepares it for cancelling any floor button calls that may be answered by car **B** on its up trip.

75 The energization of the up direction switch **BU**

closes its contact members **BU1** and **BU3**, thereby energizing the auxiliary field winding **B23** of the generator **B22** by a circuit extending from the supply conductor **L+5** through the contact members **BU1**, the field winding **B23**, the contact members **BU3** and resistor **B24R** to the supply conductor **L-5**. The closing of the contact members **BU2** energizes the brake magnet **B6** to release the brake **B5** by a circuit extending from the supply conductor **L+5** through the contact members **BU2**, the coil **B6** to the supply conductor **L-5**. The closing of the contact members **BU2** also energizes the inductor restoring relay **BEM**, the coil of which is in parallel with the brake magnet coil **B6**. The energization of the generator **B22** and the release of the brake causes the car to start upwardly.

The closing of the contact members **BU6** of up direction switch **BU** energizes the high speed relay **BV** by a circuit extending from the supply conductor **L+5** through the contact members **BU6** and **BE1** and the coil **BV** to the supply conductor **L-5**. The closing of the contact members **BV10** of the relay **BV** eliminates the resistor **B24R** from the circuit of the generator field **B23** and thereby causes the car to operate at full speed.

It will now be assumed that the attendant presses the push button **3BC** in car **B** to cause the car to stop at the third floor. The pressing of the button and the energized condition of the holding coil **3BCC** causes the contact members of the button to remain closed, thereby completing a circuit for energizing the car button stopping segment **B3c**. As the car moves up to the third floor, brush **B32** engages the energized contact segment **B3c** (Fig. 5), thereby energizing the car button relay **BCS** by a circuit extending from the supply conductor **L+6** through button **3BC**, the contact segment **B3c**, brush **B32**, the contact members **BW3** and the coil **BCS** to the supply conductor **L-6**.

The energization of the stopping relay **BCS** closes its contact members **BCS1**, thereby energizing the inductor locking relay **BEG** and the decelerating inductor relay **BE** to decelerate the car, by a circuit extending from the supply conductor **L+5** through the contact member **BCS1** thence in parallel through the coils **BEG** and **BE** and thence through the contact members **BEM2** to the supply conductor **L-5**. The energization of the relay **BEG** closes its contact members **BEG1**, thereby providing a holding circuit for that relay and for the decelerating inductor relay **BE**.

As car **B** continues its movement up to the third floor, the inductor relay **BE** passes the decelerating inductor plate **BUE** and is thereby operated to open its contact members **BE1**, thus deenergizing the high speed relay **BV**, which in turn, opens its contact members **BV10** to restore the resistor **B24R** to the circuit of the generator field winding **B23**, thus decelerating the car to its normal stopping speed.

The closing of the contact members **BV11** of the deenergized relay **BV** energizes the stopping relay **BS** and as the car continues its approach up to the third floor, the relay **BS** passes the inductor plate **BUS** and is thereby operated to open its contact members **BS1**, thus deenergizing the up direction switch **BU** which, in turn, opens its contact members to deenergize the auxiliary field winding **B23** and the brake magnet **B6**, thereby stopping the car and applying the brake **B5**.

The deenergization of the up direction switch **BU** also deenergizes the inductor restoring relay

BEM which opens its contact members BEM2 to deenergize the inductor holding relay BEG, the decelerating inductor relay BE and the stopping inductor relay BS.

5 The car B is now stopped at the third floor and the attendant opens the door and gate to permit passengers to leave the car.

It will be assumed now that a waiting passenger at the fourth floor, desirous of going to 10 a lower floor, presses the down push button 4DF at the fourth floor landing.

The operation of this button will register a down stop call at the fourth floor, it will cause the lighting of the floor lantern at the fourth 15 floor for the nearest car, and it will stop that car when it arrives on a down trip at the fourth floor, through the operation of relays as follows:

The pressing of the button 4DF energizes the stop call registering relay 4DR by a circuit extending from the supply conductor L+3 (Fig. 4) through the contact members of button 4DF, the coil 4DR and conductors 57 and 58 to the supply conductor L-3. The closing of the contact members 4DR2 of the relay 4DR completes a self-holding 25 circuit for that relay, thereby registering the call.

The closing of the contact members 4DR1 closes a gap in the circuit of the storing relay K for car A but that relay fails to become energized because car A is standing at the lower terminal with its zone brush 43 on the zone contact segment 1j whereby the zone relay 1UG is energized to open its contact members 1UG1 in the zone circuit 49 of car A, and with car B standing at the third floor on its up trip, its zone brush B36 is on the zone contact segment B3e thereby energizing zone relay 3UG to open its contact members 3UG1 in the zone circuit 49 of car A. Inasmuch as the contact members 3UG1 and 40 1UG1 in circuit 49 are open, no current can flow from the zone brush 41 of car A (now on segment 1i) to the storing relay K of car A. Thus, it is seen that the zoning system prevents the car furthest away from the registered call from 45 receiving that registered call.

The closing of the contact members 4DR3 of the energized relay 4DR completes a circuit for energizing the storing relay BK for lighting the floor lantern of car B at the fourth floor and causing car B to stop thereat when it arrives. The circuit for relay BK extends from the supply conductor L+5 (Fig. 5) through the contact members 4DR3, the coil of relay BK, contact members 4DH2 to the zone circuit B49 and thence along the zone circuit through the contact members 4DG2, 5DG2 and 4UG2 to the contact segment B3d, the brush B34 and the contact members BV9 and BY2 to the supply conductor L-6.

60 The closing of the contact members BK2 of the energized relay BK completes a self-holding circuit for that relay.

The closing of the contact members BK3 of 65 relay BK completes a circuit for lighting the down floor lantern B4DL at the fourth floor for car B and also energizes the floor selector contact segment B4g so that it will be engaged by a down brush B38 of car B and stop car B when 70 that car arrives at the fourth floor on its down trip.

The closing of the contact members BK1 of 75 relay BK energizes the preventing relay 4DH by a circuit extending from the supply conductor L+4 (Fig. 4) through the contact members

BK1 and the coil of relay 4DH to the supply conductor L-4.

The energization of the relay 4DH opens its contact members 4DH1 in the circuit of storing relay K (Fig. 3) to prevent that relay being 5 energized to stop car A if car A should pass the car B before the down call at the fourth floor is answered. The energization of the contact members 4DH2 of relay 4DH opens the original circuit to relay BK, but inasmuch as that relay 10 has closed its self-holding contact members BK2, the opening of the contact members 4DH2 has no effect thereon but serves to prevent any sneak current therethrough.

It will now be assumed that the attendant 15 on car A runs that car past car B to the upper terminal and then down past the registered down call at the fourth floor, and with that purpose in view presses the up button UP in car A. The operation of the up button UP energizes the 20 floor call cancellation relay CK and the up direction switch U by a circuit extending from the supply conductor L+ through the contact members of up button UP, the contact members S1 and D4, the coil of up direction switch U, the 25 coil of relay CK and the door and gate contact members 61 to the supply conductors L-.

The energization of up direction switch U opens its contact members U1 thereby deenergizing the down direction relay X which closes 30 its contact members X2 to energize the up direction relay W, which, in turn, closes its contact members W3 to energize the auxiliary up direction relay Y and its contact members W4 to energize the holding coils 2CC, 3CC and 4CC 35 in car A for holding the car push buttons in a depressed position after they are operated to stop the car at the different floors.

The energization of up direction switch U also closes its contact members U1 and U3 thereby 40 energizing the auxiliary field winding 23 of the generator 22 by a circuit extending from the supply conductor L+ through the contact members U1, field winding 23, the contact members U3 and the resistor 24R to the supply conductor L-6. The closing of the contact members U2 energizes the brake magnet 6 and the inductor restoring relay EM by a circuit extending from the supply conductor L- through the contact members U2 and thence in parallel 50 through the brake magnet 6 and the coil EM to the supply conductor L-. Inasmuch as the field winding 23 is now energized and the brake 5 is released by the energization of the brake magnet 6, car A starts on its up trip. Inasmuch as 55 no stop call is entered for car A, it will run to the top floor where it will be stopped by the usual limit switches (not shown).

It will be assumed now that car A runs down to the lower terminal. The car may be started in a down direction by the operation of the push button DP for energizing the down direction switch D as previously described in moving car A from the third floor to the second floor. Car A will run down to the lower terminal and 65 will be stopped at that terminal in the usual manner by the limit switches (not shown).

It will be observed that car A passed car B and also passed the registered down call at the fourth floor without being affected thereby in 70 any manner. The fact that the registered down call at the fourth floor failed to affect car A is due to the open contact members 4DH1 in the circuit of the storing relay K for the fourth floor for car A, it being obvious that although the 75

contact members **4DR1** in the circuit relay **K** were closed, the remainder of the circuit could not be completed even though the live brush **40** of car **A** engaged the contact segment **4i** leading to the storing relay **K** for the fourth floor.

It will now be assumed that car **B** is run to the top floor and then down to answer the registered down call at the fourth floor. The attendant in car **B** now presses the up button **BUP** 10 to cause the car to move upwardly as previously described. When the car reaches the upper terminal, it is stopped by the usual limit switches (not shown) and it is started on its down trip by the attendant operating the down push button **BDP** which closes its contact members to energize the floor button cancelling relay **CK** and the down direction switch **BD** by a circuit extending from the supply conductor **L-5** (Fig. 5) through the contact members of button **BDP**, 15 the contact members **BS2** and **BU5**, the coil of down direction switch **BD**, the coil of relay **BCK** and the door and gate contact members **B61** to the supply conductor **L-5**.

The opening of the contact members **BD1** of 25 the down direction switch **BD** deenergizes the up direction preference relay which thereupon closes its contact members **BW2**, thus energizing the down direction preference relay **BX** by a circuit extending from supply conductor **L-5** 30 through the coil **BX** and the contact members **BU7** and **BW2** to the supply conductor **L-5**. The opening of the contact members **BX2** of relay **BX** locks out the up direction preference relay **BW**. The closing of the contact members **BX3** 35 completes a circuit for energizing an auxiliary down direction preference relay **BZ**. The opening of the contact members **BW4** deenergizes the auxiliary up direction preference relay **BY**.

The closing of the contact members **BX5** and 40 the opening of contact members **BW5** causes the car button holding coils **2BCC**, **3BCC** and **4BCC** to be deenergized at the limit of the up trip and to be immediately energized again for the down trip.

45 Returning now to the energization of the down direction switch **BD**, the closing of its contact members **BD1** and **BD2** energizes the field winding **B23** by a circuit extending from the supply conductor **L-5** through the contact members **BD2**, the field winding **B23**, the contact members **BD1** and the resistor **B24R** to the supply conductor **L-5** for starting car **B** in the down direction.

The energization of the down relay **BD** also 50 closes its contact members **BD6** thereby energizing the high speed relay **BV** through a circuit extending from the supply conductor **L-5** through the contact members **BD6** and **BE2** and the coil of relay **BV** to the supply conductor **L-5**.

The energization of the relay **BV** closes its contact members **BV10** thereby eliminating the resistor **B24R** from the circuit of the auxiliary field winding **B23** thus causing car **B** to accelerate to 65 full speed.

As car **B** continues downwardly, its brush **B38** engages the live contact segment **B4g** thereby energizing the floor button stopping relay **BFS** by a circuit extending from the supply conductor 70 **L-6** through the contact members **BK3**, contact segment **B4g**, brush **B38**, contact members **Bz3**, and the coil of relay **BFS** to the supply conductor **L-6**.

The energized relay **BFS** closes its contact 75 members **BFS1** thereby energizing the inductor

locking relay **BEG** and the inductor decelerating relay **BE** to decelerate the car by a circuit extending from the supply conductor **L-5** through the contact members **BFS1**, thence in parallel through the coils of relays **BEG** and **BE** and 5 thence through the contact members **BEM2** to the supply conductor **L-5**.

As the car passes the down inductor plate **BDE** in approaching the fourth floor, the energized decelerating inductor relay **BE** is operated 10 to open its contact members **BE2** thereby de-energizing the high speed relay **BV** which, in turn, opens its contact members **BV10** thereby restoring the resistor **B24R** to the circuit of the field winding **B23** thus decelerating the car to 15 its normal stopping speed.

The deenergization of the relay **BV** closes its contact members **BV11** thereby energizing the stopping inductor relay **BS** to stop the car.

As the car approaches closely to the fourth 20 floor landing, the stopping inductor relay **BS** comes adjacent to the inductor plate **BDS** and is thereby operated to open its contact members **BS2** thereby deenergizing the down direction switch **BD** which opens its contact members 25 **BD1**, **BD2** and **BD3** to deenergize the field winding **B23** and the brake magnet **B6**, thus stopping the car **B** at the fourth floor in answer to the down stop call registered on the push button **4DF** 30 at the fourth floor.

Hence it is seen that the registration of a down stop call at the fourth floor while car **B** was on an up trip at the third floor immediately caused the lighting of the down signal lantern at the fourth floor for car **B** and stopped car **B** when 35 it arrived at the fourth floor. In other words, the registered call caused the next car for down service at the fourth floor to immediately light its signal and stop when it arrived.

An assumed operation of the bypassing or 40 transfer means whereby a car attendant may cause his car to bypass a stop call registered on a floor push button, without answering the call and at the same time cause the registered call to be transferred to the next nearest approaching 45 car for the corresponding direction, is as follows:

It will be assumed that the cars have been moved so that car **A** is now at the third floor on a down trip and car **B** is at the second floor 50 on an up trip, in the same position and operating in the same direction as they were in first starting the operation of the cars. It will also be assumed that a waiting down passenger at the second floor has operated the down button **2DF** at that floor to cause a car to stop for him. As previously described the operation of the down button **2DF** causes the nearest approaching car in the desired direction (now car **A**) to give an immediate signal indicating the door at which 60 it will stop and will also cause the car to stop when it arrives at that floor on its "down" trip unless the bypass transfer button in that car is operated.

The pressing of the button **2DF** operates the 65 registering relay **2DR** which in turn energizes the storing relay **M** for car **A**. The operation of relay **M** energizes the preventing relay **2DH** which opens its contact members **2DH2** to prevent energization of the storing relay **BM** of car **B**, lights 70 the down floor lantern **2DL** at the second floor for car **A** and energizes the contact segment **2g** to stop car **A** when it arrives at the second floor. The circuits and the opening and closing of the various contact members which follow the oper- 75

ation of the down button 2DF are the same as in the first operation described for the cars in connection with the button 2DF and therefore will not be now repeated.

- 5 Although the operation of the push button 2DF has registered the passenger's stop call for car A, it will be assumed that the attendant on car A desires to run his car as an express from the third floor down to the lower terminal and therefore 10 by avoiding answering the registered call for the intervening floor. In order to accomplish this result, the car attendant starts the car A downwardly as previously described and at the same time presses the bypass or transfer button 45 in 15 his car to bypass any hall calls registered for him and transfer them to the next following car.

The pressing of the bypass button 43 (which must be continued during the bypassing period) energizes the bypass or transfer relay PS by a 20 circuit extending from the conductor L+ through the coil PS and the contact members of button 45 to the supply conductor L-. The energized relay PS opens its contact members PS1, PS2, PS3 and PS4. The opening of the contact members PS1 deenergizes the auxiliary down direction preference relay Z for car A which opens its contact members Z3 to electrically disconnect the zone relay brushes 42 and 43 of car A from the zone relays 4DG, etc., thereby removing car A 30 from signal zone operation. The opening of the contact members Z2 electrically disconnects the brushes 40 and 41 from the storing relays K, L, etc., thereby deenergizing any energized storing relay for car A and also preventing their energization 35 during the bypass operation. The opening of the relay contact members Z1 electrically disconnects the down brush 38 from the floor selector stopping contact segments 2g, etc., thereby preventing operation of the circuits for stopping the 40 car A in response to registering hall calls on its down trip.

The opening of the contact members PS2 of the relay PS opens the self-holding circuit for all of the up storing relays of car A.

- 45 The opening of the contact members PS3 opens the self-holding circuit for all of the down storing relays for car A including the relay M (Fig. 3) and thereby deenergizes that relay so that it no longer stores and appropriates to car A the down stop 50 call registered at the second floor.

When the storing relay M for car A is deenergized, it opens its contacts members M3 in the circuit of the preventing relay 2DH thereby causing that relay to be deenergized and in turn close 55 its contact members 2DH2 in the circuit of the storing relay BM for car B, to cause that relay to store and appropriate to car B the down registered call at the second floor. The circuit for relay BM extends from the supply conductor 60 L+5 through the now closed contact members 2DR3, coil BM, contact members 2DH2, to zone circuit B49, and thence through contact members 2DG2, 3DG2, 4DG2, 5DG2, 4UG2 and 3UG2, contact segment B2d, brush 34 and the contact 65 members BV9 (because car B is standing at second floor up) and BY2 to the supply conductor L-6.

Upon being energized, the storing relay BM closes its contact members BM2 thereby creating a self-holding circuit for itself extending from the coil BM through the contact members BM2, BT11, and BPS2 to the supply conductor L-5.

The closing of the contact members BM1 again 70 energizes the preventing relay 2DH to in turn

open its contact members 2DH1 in the circuit of the storing relay M for car A to prevent energization of that relay.

It will be assumed now that the attendant on car A, while pressing the button 45, operates 5 that car to run it to the lower terminal as previously described. In so doing, the down hall stopping brush 38 engages the contact segment 2g on the floor selector, but, inasmuch as the transfer of the down second floor call from car A 10 to car B has taken place, the storing relay M is deenergized, its contact members M1 are open, and the segment 2g is dead. Therefore, the contact of brush 38 with segment 2g does not energize the relay FS to stop car A at the second 15 floor. Hence it is seen that as long as the attendant in car A keeps pressing the bypass button in car A, that car will bypass any hall calls and will transfer them to the next nearest approaching car, even though that car may, at the 20 same time, be going in the opposite direction.

Also, inasmuch as the energization of the transfer relay PS has opened its contact members PS4 in the circuit of the down cancellation brush 37 of car A, that car will not cancel the 25 registered down call at the second floor as it passes that floor in moving down to the lower terminal.

The opening of the contact members M1 of 30 the deenergized storing relay M also deenergized and extinguished the down signal lantern 2DL for car A at the second floor. At the same time, the storing relay BM for car B closed its contact members BM3, thereby energizing the 35 down signal lantern B2DL for car B at the second floor. The extinguishing of down lantern 2DL for car A and the lighting of the down lantern B2DL for car B at the second floor notifies the waiting passenger at the second floor that his stop call has been transferred from car A to car 40 B so that he may move from the door of car A to the door of car B and be ready to board that car when it arrives.

It will now be assumed that the car B has run 45 up to the upper terminal and has started on a down trip as previously described. As car B approaches the registered down stop call at the second floor, its brush B38 engages the energized contact segment B2g and thereby energizes 50 the floor stopping relay BFS of car B by a circuit extending from the supply conductor L+6 through the contact members BM3, contact segment B2g, brush B38, contact members BZ3 and coil BFS to the supply conductor L-6. The 55 energization of the floor stopping relay BFS causes the car stopping inductor system to fall into operation as previously described and thereby effects the stopping of car B at the second floor on its down trip.

By reason of the foregoing it will be seen that when the attendant in a car bypasses the outside hall stop calls, he also transfers the call to the next following car and so operates the floor signal lanterns at the floors as to indicate to 65 waiting passengers that their calls have been transferred and also the car to which they have been transferred.

Assumed operation of the system with relays T and BT energized

The system will now be operated after closing the system selecting push buttons 47 for car A and B47 for car B, thereby energizing the system selecting relays T and BT, to so open such 75

contact members and close such contact members in the elevator system that when a stop push button is operated at a floor landing, the first car to arrive in the desired direction will 5 stop in response to the operation of the push button. In other words, if one car passes another car it will automatically transfer to itself the calls on the passed car.

When the relays T and BT are energized, they 10 open contact members which disconnect the circuits of the storing relays leading to the minus supply conductors. At the same time, they close contact members which short circuit the preventing relay contact members in the storing relay 15 circuits leading to the ring circuits controlled by the zone relays. For instance, in Fig. 3, when relay T is energized it opens its contact members T3 in the circuit from storing relay K to supply conductor L-. Hence, the storing relay will remain 20 energized (if energized) only so long as the zone ring circuit 49 will permit in accordance with the position of the cars. At the same time, the closing of the contact members T1 will short circuit the preventing relay contact members 25 4DH1 in the storing relay circuit. Therefore, the storing relays will be energized after the operation of a floor stop button, in accordance with the position of the cars, and will change when the positions of the cars change. The following 30 operation will make clearer the effect of energizing the system relays T and BT.

It will be assumed that the cars are disposed as they were left in the last operation; that is, car A at the lower terminal and car B standing 35 at the fourth floor on a down trip.

It will also be assumed that a passenger at the fourth floor desires to go to the upper terminal, and presses the up push button 4UF to cause the next up car to stop for him. The operation of 40 the button will cause an immediate lighting of the signal lantern of the nearest car and will cause the first car to arrive to stop, through the operation of the following relays.

The pressing of the push button 4UF energizes 45 the up call registering relay 4UR at the fourth floor by a circuit extending from the supply conductor L+3 (Fig. 4) through the contact members of push button 4UF, the coil of relay 4UR and the conductors 57 and 58 to the supply conductor L-3.

The energization of the registering relay 4UR closes its contact members 4UR2, thereby providing a self-holding circuit. The up stop call at the fourth floor is now registered and will remain 55 registered until a car answers the call and restores the registering relay to its normal condition.

The closing of the contact members 4UR3 of relay 4UR closes one gap in a circuit leading to 60 the storing relay BN of car B, but that relay is not energized for the following reasons:

Inasmuch as car A standing at the lower floor with its zone brush 43 disposed on the zone segment 1j, the zone relay 1UG is energized by a 65 circuit extending from the supply conductor L+4 through the coil of relay 1UG, contact segment 1j, brush 43 and the contact members V8 and Z3 to the supply conductor L-4. The energized relay 1UG opens its contact members 1UG1 in the zone circuit 49 of car A and its contact members 1UG2 in the zone circuit B49 for car B. Inasmuch as car B is standing at the fourth floor on its down trip, the brush B43 is disposed on its contact segment B4j, thereby energizing zone 70 relay 4DG by a circuit extending from supply 75

conductor L+4 through the coil of relay 4DG, the contact segment B4j, brush B43 and the contact members BV1 and BZ1 to the supply conductor L-4.

Inasmuch as the zone relay contact members 1UG2 and 4DG2 in the zone circuit B49 are open, the down brushes B41 and B40 are prevented from completing a circuit through the contact segments B4i or B3i of the zone circuit B49 to the intersection point 65 leading to the coil of storing relay BN. Therefore, the registration of the stop call on the button 4UF has no effect upon car B or its storing relay BN at the present time.

The closing of the contact members 4UR1 of the relay 4UR completes a circuit for energizing the storing relay N of car A, which circuit extends from supply conductor L+2 through the contact members 4UR1, the storing relay coil N, the contact members 4UH1, the junction point 66 in zone circuit 49, and thence through the contact members 4UG1, 3UG1 and 2UG1 to the contact segment 1i, brush 41, and the contact members V3 and Z2 to the supply conductor L-. Although the zone contact segments 4DG1 and 1UG1 in the zone circuit 49 are open, they do not 25 prevent the passage of current through a sufficient portion of the zoning circuit 49 to energize the storing relay N.

The energization of the storing relay N closes its contact members N2 to provide a self-holding 30 circuit for itself.

The energization of the relay N closes its contact members N1 to light the floor lamp 4UL and to energize the floor selector contact segment 4b in preparation for stopping the car A when it 35 approaches the fourth floor. It will be observed that the lighting of the floor lamp 4UL immediately follows the energization of the relay 4UR and thereby constitutes an immediate signal to the waiting passenger at the fourth floor to advise that passenger that car A has been conditioned to stop for him and the door at which it will stop.

The energized preventing relay 4UH opens its contact members 4UH1 in the circuit for the 45 storing relay N, and its contact member 4UH2 in the circuit to the storing relay BN, thereby preventing the occurrence of sneak circuits through the floor selector segments and brushes.

It will now be assumed that car A remains at 50 the lower terminal and that the attendant on car B runs that car down to the lower terminal, passes car A, and then runs car B up toward the upper terminal.

Car B is started downwardly by the attendant 55 operating the push button switch BDP in the car. Thereupon car B moves down to and is stopped at the lower terminal by the usual limit switches (not shown). As car B stops at the lower terminal, its high-speed relay BV is de- 60 energized, thus opening its contact members BV2 and closing its contact members BV1, thereby maintaining the zoning relay 1UG in an energized condition through the brush B43 now on contact segment B4j.

Both the cars B and A are now at the lower terminal, and both cars have completed circuits for energizing the zoning relay 1UG. However, car B will not yet respond to the registered up call at the fourth floor, because the preventing relay 4UH is still energized and its contact members 4UH2 in the circuit leading to the storing relay BN are open, which prevents that relay from being energized even though the zone circuits might otherwise permit it.

It will now be assumed that the attendant on car B presses the up button BUP to move the car upwardly, as previously described.

Inasmuch as car B is now passing car A, car 5 B will take the registered stop call at the fourth floor away from car A in the following manner.

As car B starts upwardly, its high-speed relay BV closes its contact members BV4, leading to brush B35 (Fig. 4) in engagement with the contact segment B2e, thereby energizing the zone relay 2UG by a circuit extending from the supply conductor L+4 through the coil of relay 10 2UG, conductor 64, contact segment B2e, brush B35, and the contact members BV4 and BY1 15 and supply conductor L-4.

The energization of the zone relay 2UG opens its contact members 2UG1 in the zone circuit 49 of car A. Inasmuch as the zone contact members 1UG1 also are open because car A is standing at the bottom terminal, and the contacts 2UG1 are open because car B is starting on an up trip, the circuit through brush 41 of car A on contact segment 4i is now open and current cannot reach the storage relay N. Therefore, 25 that relay is now deenergized.

The deenergization of the storing relay N opens its contact members N1, thereby extinguishing the up floor lantern 4UL for car A at the fourth floor, deenergizing the car A stopping contact segment 4b, and also deenergizing the preventing relay 4UH. The deenergization of relay 4UH closes its contact members 4UH1 in the circuit for the storing relay N for car A and also closes its contact members 4UH2 in the 35 circuit for the storing relay BN for car B.

Inasmuch as the registering relay 4UR remains energized, its contact members 4UR3 are still closed. The storing relay BN of car B is now energized by a circuit extending from the supply conductor L+6 (Fig. 5) through the contact members 4UR3, the coil of relay BN, the contact members 4UH2, the junction 65 with zone circuit B49, zone contact members 4UG2 and 3UG2, the contact segment B2d, brush B33, 45 and the contact members BV1 and BY2 to the supply conductor L-6.

The energization of the storing relay BN closes its contact members BN2 to complete a self-holding circuit for itself.

50 The closing of the contact members BN3 of relay BN lights the floor lantern B4UL to indicate to the waiting passenger that car B having passed car A will answer the registered stop call at the fourth floor. The closing of the contact members BN3 also energizes the up contact segment B4b for stopping car B as it comes to the fourth floor. It will thus be observed that the movement of car B to its present position has transferred the registered call from the storing relay N of car A to the storing relay BN of car B; that is, car B has taken the fourth floor call away from car A and will itself answer the call.

As car B approaches the fourth floor, its brush B31 engages the energized segment B4b and thereby energizes the floor button stopping relay BFS to stop the car, by a circuit extending from the supply conductor L+6, the contact members BN3, the contact segment B4b, brush B31, the contact members BY3 and the coil of stopping 65 relay BFS to the supply conductor L-6.

The energized relay BFS closes its contact members BFS1, thereby energizing the inductor locking relay BEG and the decelerating inductor relay BE by a circuit previously described.

75 The energization of the locking relay BEG

closes its contact members BEG1, thereby providing a self-holding circuit for itself and the inductor relay BE.

As car B approaches more closely to the fourth floor, the inductor relay BE comes opposite the inductor plate BUE, and is thereby operated to open its contact members BE1, thus deenergizing the high-speed relay BV which in turn opens its contact members BV10, thereby restoring the resistor B24R to the circuit of the field winding 10 B23, thereby decelerating the car to its normal stopping speed.

The deenergization of the high-speed relay BV also closes its contact members BV11, thereby energizing the stopping inductor relay BS. 15

As the car approaches still more closely to the fourth floor landing, the inductor relay BS comes opposite the inductor plate BUS which opens its contact members BS1, thereby deenergizing the up direction switch BU which in turn deenergizes 20 the field winding 23 and the brake magnet B6 to stop the car level with the floor.

It will be assumed that the car attendant opens the door, admits the passenger, and starts the car B up to the upper terminal. As the car moves 25 away from the fourth floor, the cancelling relay BCK is energized, as previously described, to close its contact members BCK1 (Fig. 4) and the inductor restoring relay BEM is energized to restore the inductor relays. 30

The contact members BCK1 remain closed, and the contact members BEM2 of relay BEM fail to open for a sufficient period after the relay BEM is energized to energize the restoring coil 4URS, by a circuit extending from the supply conductor 35 L+3 through the contact members 4UR2, the restoring coil 4URS, the contact segment 4A, brush 30, and the contact members W5, PS4, EN2 and CK1 to the supply conductor L-3.

The energization of the restoring coil 4URS 40 deenergizes the registering relay 4UR thereby cancelling the stop call registered at the fourth floor.

It may be noted here that the upper end of the stem of inductor restoring relay BEM is connected to the main portion of the stem by a spring 67 which permits the upper end portion to be retarded in action by a dashpot 68, for a sufficient length of time to permit the energization of the coil for restoring the registered relay 50 4UR.

In view of the foregoing description, it will be understood that I have provided an elevator system in which a waiting passenger at a floor will, upon pressing a stop button at the floor to 55 cause a car to stop for him, receive an immediate signal in response indicating which car will stop for him and the door to which he should go to board the car when it comes to the floor and will also cause the car to stop for him without 60 any stopping operation on the part of the attendant in the car.

Furthermore, the system may be conditioned by means of system selecting relays to so operate that either the nearest car in the desired direction will appropriate the call and give an immediate response and make the stop itself or to so operate that the nearest car in the desired direction will give an immediate response and answer the signal but if another car passes that car, 65 the passing car will take the signal away from the passed car and itself give a signal and make the stop in response to the call.

Although I have illustrated and described only one specific embodiment of my invention, I 75

realize that it is susceptible of wide application and I do not desire to be limited to the precise system illustrated and described.

I claim as my invention:

5. 1. In an elevator system for operating a plurality of cars past a floor, a signal device for each car at the floor, a control device at the floor common to all the cars, and means responsive to operation of the control device for immediately 10 operating only the signal device corresponding to the nearest approaching car and for stopping a car upon its arrival at the floor.
15. 2. In an elevator system for operating a plurality of cars past a floor, a signal device for each car at the floor, a control device at the floor common to all the cars, and means responsive to operation of the control device for immediately 15 operating only the signal device corresponding to the nearest approaching car and for stopping 20 that car upon its arrival at the floor.
25. 3. In an elevator system for operating a plurality of cars past a floor, a signal device for each car at the floor, a control device at the floor common to all the cars, and means responsive to operation of the control device for immediately 20 operating only the signal device corresponding to the nearest approaching car and for stopping the first car to arrive at the floor.
30. 4. In an elevator system for operating a plurality of cars past a plurality of floors, a plurality of signal devices, one for each car at each floor for the up direction and one for each car at each floor for the down direction, an up control device at each floor common to all the cars, 30 a down control device at each floor common to all the cars, means responsive to operation of the up control device at any floor for immediately operating only the signal device at that floor for the nearest approaching car in the up direction 40 for that floor and for stopping a car when it arrives at that floor in the up direction, and means responsive to the operation of the down control device at any floor for immediately operating only the down signal device at that floor for the nearest approaching car in the down direction for that floor and for stopping a car when it arrives at that floor in the down direction.
45. 5. In an elevator system for operating a plurality of cars past a plurality of floors, a plurality of signal devices one for each car at each floor for the up direction and one for each car at each floor for the down direction, an up control device at each floor common to all the cars, a down control device at each floor common to all the cars, means responsive to operation of the up control device at any floor for immediately operating only the signal device at that floor for the nearest approaching car in the up direction and for stopping that car when it arrives at that floor, and means responsive to the operation of the down control device at any floor for immediately operating only the down signal device at that floor for the nearest approaching car in the down direction for that floor and for stopping that car when it arrives at that floor.
55. 6. In an elevator system for operating a plurality of cars past a plurality of floors, a plurality of signal devices, one for each car at each floor for the up direction and one for each car at each floor for the down direction, an up control device at each floor common to all the cars, a down control device at each floor common to all the cars, means responsive to the operation of the up control device at any floor for immediately operating only the signal device at that floor for the nearest approaching car in the up direction and for stopping the next car to arrive at that floor for up direction service thereat, and means responsive to operation of the down control device at any floor for immediately operating only the down signal device at that floor for the next car for down direction service at that floor and for stopping the next car to arrive at that floor for down service thereat.
65. 7. In an elevator system for operating a plurality of cars past a plurality of floors, a plurality of signal devices, one for each car at each floor for the up direction and one for each car at each floor for the down direction, an up control device at each floor common to all the cars, a down control device at each floor common to all the cars, means responsive to operation of the up control device at any floor for always immediately operating the signal device at that floor for the next car for up direction service at that floor regardless of its then direction of operation and for stopping a car when it arrives at that floor in the up direction, and means responsive to the operation of the down control device at any floor for immediately operating the down signal device at that floor for the next car for down direction service at that floor and for stopping a car when it arrives at that floor.
70. 8. In an elevator system for operating a plurality of cars past a plurality of floors, a plurality of signal devices one for each car at each floor for the up direction and one for each car at each floor for the down direction, an up control device at each floor common to all the cars, a down control device at each floor common to all the cars, means responsive to operation of the up control device at any floor for immediately operating only the signal device at that floor for the next car for up direction service at that floor and for stopping that car when it arrives at that floor in the up direction, and means responsive to operation of the down control device at any floor for immediately operating only the down signal device at that floor for the next car for down direction service at that floor and for stopping that car when it arrives at that floor.
75. 9. In an elevator system, for operating a plurality of cars past a plurality of floors, a plurality of signal devices, one for each car at each floor for the up direction and one for each car at each floor for the down direction, an up control device at each floor common to all the cars, a down control device at each floor common to all the cars, means responsive to operation of the up control device at any floor for immediately operating only the signal device at that floor for the next car for up direction service at that floor and for stopping the next car to arrive at that floor for up direction service thereat, and means responsive to operation of the down control device at any floor for immediately operating only the down signal device at that floor for the next car for down direction service at that floor and for stopping the next car to arrive at that floor for down service thereat.
80. 10. In an elevator system for operating a plurality of cars past a plurality of floors, a plurality of signal devices, one for the up direction for each car at each floor and one for the down direction for each car at each floor, an up call registering means for each floor common to all the cars, a down call registering means for each floor common to all the cars, means responsive to the registration of an up stop call at any floor and to the position of the nearest approaching car

in the up direction for immediately operating the up signal device of that car at that floor and for stopping that car upon its arrival at that floor and for preventing the said registered call from 5 operating the signal device of any other car or stopping any other car, and means responsive to the registration of a down stop call at any floor and to the position of the nearest approaching car in the down direction for immediately operating 10 the down signal device of that car at that floor and for stopping that car upon its arrival at that floor and for preventing the said registered call from operating the signal of any other car or stopping any other car.

15 11. In an elevator system for operating a plurality of cars past a plurality of floors, a plurality of signal devices one for the up direction for each car at each floor and one for the down direction for each car at each floor, an up call registering 20 means for each floor common to all the cars, a down call registering means for each floor common to all the cars, means responsive to the registration of an up stop call at any floor and to the position of the next car for up direction service 25 at that floor for immediately operating the up signal device of that car at that floor and for stopping that car at that floor upon its arrival at that floor for the direction of the registered call and for preventing the said registered call 30 from operating the signal of any other car or stopping any other car, and means responsive to the registration of a down stop call at any floor and to the position of the next car for down direction service at that floor for operating the 35 down signal device of that car at that floor and for stopping that car upon its arrival at that floor for the direction of the registered call and for preventing the said registered call from operating the signal of any other car or stopping any 40 other car.

12. A control system for a plurality of elevator cars comprising, means for stopping each car at a landing, means common to all the cars for causing the operation of the stopping means for but 45 one of the cars approaching the landing, said means comprising means to operate immediately a signal associated with said car at said landing regardless of the position and direction of operation of said car, and means for preventing the 50 operation of said stopping means for the other cars until after the first named car is prepared to leave the landing.

13. In an elevator system for operating a plurality of cars past a plurality of floors, a plurality of signal devices, one for each car at each floor for the up direction, and one for each car at each floor for the down direction, an up control device at each floor common to all the cars, a down control device at each floor common to all the 60 cars, means responsive to operation of the up control device at any floor for immediately operating the signal device at that floor for only the next car for up direction service at that floor regardless of its direction of travel at the time of 65 operation of the control device, and means responsive to the operation of the down control device at any floor for immediately operating the down signal device at that floor for only the next car for down direction service at that floor regardless of its direction of travel at the time of 70 operation of the control device.

14. In an elevator system for operating a car past a plurality of floors, a ring circuit for the car, said circuit comprising a plurality of sections, means responsive to operation of the car for

electrically separating two of the sections, a plurality of contact segments, each segment being connected to one of the sections of the ring circuit, an advance brush and a standing brush, means responsive to operation of the car for moving the brushes over the contact segments in accordance with the movements of the car, a power circuit for connecting said brushes to a source of electrical energy and means responsive to operation of the car for opening said power circuit to the standing brush when the car is running and for opening the power circuit to the advanced brush when the car is standing. 5

15. In an elevator system for operating a plurality of cars past a plurality of floors, a plurality of ring circuits one for each car and each ring circuit including a plurality of sections, a plurality of relays connected to said ring circuits, means for connecting said relays to one side of a supply circuit, means responsive to operation of the cars 20 for dividing each ring circuit into a plurality of zone portions including one or more sections in accordance with the number and position of the cars, a plurality of contact segments connected to the sections of the ring circuit for each car, one 25 for each section, an advance brush and a standing brush for each car, means responsive to operation of each car for moving the brushes for that car over the contact segments for that car in accordance with the movements of that car, 30 circuits for connecting the brushes to the other side of the supply circuit, and means responsive to the operation of each car for opening the circuit to the standing brush for that car when that car is running and for opening the circuit to the 35 advance brush of that car when that car is standing.

16. In an elevator system for operating a plurality of cars past a plurality of floors, a plurality of signal devices, one for the up direction for each 40 car at each floor and one for the down direction for each car at each floor, an up control device for each floor common to all the cars for registering an up stop call at that floor, a down control device for each floor common to all the cars for 45 registering a down stop call at that floor, a control system responsive to the registration of a stop call for immediately operating the signal at the floor at which the call is registered for the next car for the direction of the call and a system 50 selecting means for conditioning the control system to stop the first car to pick up the registered call or for conditioning the control system to stop the first car to arrive in the desired direction at the floor at which the registered call exists. 55

17. In an elevator system for operating a plurality of cars past a plurality of floors, a plurality of signal devices, one for the up direction for each car at each floor and one for the down direction for each car at each floor, an up control 60 device for each floor common to all the cars for registering an up stop call at that floor, a down control device for each floor common to all the cars for registering a down stop call at that floor, a control system responsive to the registration of a stop call for immediately operating the signal at the floor at which the call is registered for the next car for the direction of the call and a system 65 selecting means comprising electromagnetic means which may be conditioned in one manner to cause the control system to stop the first car to pick up the registered call or in another manner to cause the control system to stop the first car to arrive in the desired direction at the floor at which the registered call exists. 70

- of signal devices one for each car at each floor for the up direction and one for each car at each floor for the down direction, an up call registering means for each floor common to all the cars, 5 a down call registering means for each floor common to all the cars, means responsive to the registration of a stop call at a floor for immediately operating the signal device at that floor in the direction of the registered call for the next car 10 for service at that floor, and means responsive to the position of the first car to overtake said next car for restoring the operated signal device of the overtaken car, for operating the signal device of the overtaking car and for causing said 15 overtaking car to stop at said floor.
26. In an elevator system for operating a plurality of cars past a plurality of floors, a plurality of signal devices one for the up direction for each car at each floor and one for the down direction for each car at each floor, an up call registering means for each floor common to all the cars, a down stop call registering means for each floor common to all the cars, a plurality of up storing devices, one for each car for each 25 floor, a plurality of down storing devices, one for each car for each floor, said storing devices being operably responsive to the registration of a stop call at a floor and the position of the next car for service at that floor in the direction of the 30 registered call for immediately operating the signal device of said next car at the floor of the registered call in the direction of the registered call and for effecting the stopping of a car at the floor of the registered call, and means responsive to the position of the first car to overtake said 35 next car for restoring the operated signal device of the overtaken car and for operating the corresponding signal device of the overtaking car.
27. In an elevator system for operating a plurality of cars past a plurality of floors, a plurality of signal devices, one for the up direction for each car at each floor and one for the down direction for each car at each floor, an up stop call registering means for each floor common to 40 all the cars, a down stop call registering means for each floor common to all the cars, storing means responsive to the registration of a stop call at a floor, and to the position of the next car for service at that floor in the direction of the registered call, for storing that call and assigning it to said next car and for immediately operating the signal device at that floor for said next car in the corresponding direction, and means responsive to the operation of the first 45 car to overtake said next car for transferring the stored up call from the storing means for the overtaken car to the storing means for the overtaking car to restore the signal device of the overtaken car, to immediately operate the corresponding signal device of the overtaking car and to effect the stopping of the overtaking car at the floor at which the stop call is registered. 50
28. In an elevator system for operating a plurality of cars serving terminal floors and intermediate floors, a down signal device for each car at the upper terminal floor and at each intermediate floor, an up signal device for each car at the lower terminal floor and at each intermediate floor, a down control device at the upper 55 terminal floor and at each intermediate floor common to all the cars, an up control device at the lower terminal floor and at each intermediate floor common to all the cars, means responsive to operation of the down control device at any floor for immediately operating the signal 60
- device at that floor for the next car for down direction service at that floor, regardless of the direction of operation of the car at the time the control means is operated, and means responsive to operation of the up control device at any 5 floor for immediately operating the up signal device at that floor for the next car for up direction service at that floor, regardless of the direction of operation of the car at the time the control device is operated. 10
29. In a signalling system for a plurality of elevators operable past a floor, a switch at said floor for signalling a car for travel in a given direction, a plurality of signal devices at said floor one associated with each car to indicate 15 car travel in the given direction, a plurality of mechanisms one for each car, driven in accordance with movements of said car, means common to all of the cars and operably responsive to said mechanisms and cooperating with 20 said mechanisms for controlling the signal lights at said floor, said means being responsive at any time to the operation of said switch for operating the signal of the car nearest said floor for travel in the given direction, regardless of the 25 direction of travel of said car.
30. In an elevator system for operating a plurality of cars past a plurality of floors, a plurality of signal devices, one for the up direction for each car at each floor and one for the down 30 direction for each car at each floor, an up call registering means for each floor common to all the cars, a down stop call registering means for each floor common to all the cars, a plurality of up storing relays, one for each car for each 35 floor, a plurality of down storing relays, one for each car for each floor, said storing relays being operably responsive to the registration of a stop call at a floor and the position of the next car for service at that floor in the direction of the registered call for immediately operating the signal device of said next car at the floor of the registered call in the direction of the registered call and for effecting the stopping of that car at that floor, and a plurality of preventing relays 40 operably responsive to operation of the storing relays for preventing said registered call from causing operation of the signal device of any other car or stopping any other car. 45
31. A system for operating a plurality of cars 50 comprising means for registering calls for the cars; relay means individual to each of said cars for storing a registered call corresponding to that car; a transfer means for each car, and means responsive to operation of said transfer 55 means for transferring a call stored by the relay means for one of said cars to the relay means for another of said cars.
32. In an elevator system for operating a plurality of cars past a plurality of floors, means for 60 registering stop calls for the cars, relay means individual to each of said cars for storing registered calls for the cars in accordance with their position and direction of operation in relation to the registered calls, a transfer means for 65 each car, and means responsive to operation of a transfer means for transferring all the calls stored by the relay means of one of said cars to the corresponding relay means of the next following car. 70
33. In an elevator system for operating a plurality of cars past a plurality of floors, an up stop call registering means for each floor common to all the cars, a down stop call registering means for each floor common to all the cars, 75

- relay means individual to each of said cars for storing registered calls corresponding to that car, a transfer means for each car, and means, including means controlled in accordance with the position and direction of operation of the cars, responsive to an operation of the transfer means of a car for transferring all calls stored by the storing relays of that car to the corresponding storing relays of the next following car.
34. In an elevator system for operating a plurality of cars past a plurality of floors, a plurality of signal devices, one for the up direction for each car at each floor and one for the down direction for each car at each floor, an up call registering means for each floor common to all the cars, a down stop call registering means for each floor common to all the cars, a plurality of up storing relays, one for each car for each floor, a plurality of down storing relays, one for each car for each floor, said storing relays being operably responsive to the registration of stop calls at the floors and the position and direction of operation of the cars for immediately operating the signal device of the next car for service at the floor of a registered call in the direction of the registered call and for effecting the stopping of that car at that floor, a transfer means for each car, and means responsive to operation of a transfer means for transferring all calls stored by the storing relays of one car to the corresponding storing relays of the next following car.

WILLIAM F. EAMES.
